WINDING DEVICE FOR SPOOLS OF SURGICAL STITCHING INSTRUMENTS

John D. Karle, Roselle Park, N. J., assignor to
The Singer Manufacturing Company, Elizabeth, N. J., a corporation of New Jersey

Application June 24, 1941, Serial No. 399,444

9 Claims. (Cl. 242—96)

This invention relates to devices for winding suturing thread on spools adapted to be used in surgical stitching instruments of that type in which a curved eye-pointed needle is rigidly secured at one end of a rod-like support and the suturing thread is continuously supplied to the needle from a spool carried by the instrument.

A primary object of the invention is to provide improved and simplified manually actuated means, adapted to be supported either by the instrument, or by a separate element, to wind the suturing thread onto the spool for subsequent use in the instrument.

This and other objects have been attained by the construction hereinafter described and illustrated in the accompanying drawing in which:

Fig. 1 is an elevational view, partly in section, of a surgical stitching instrument having my improved spool winding means connected thereto.

Fig. 2 is a view in elevation of the right hand end of Fig. 1 looking in the direction indicated by the arrow x.

Fig. 3 is a disassembled perspective view of the various elements of my improved spool winder, together with the spool adapted to be wound thereby.

Fig. 4 is a central sectional view of the spool shown in Fig. 3.

Fig. 5 is a perspective view, on an enlarged scale, of a portion of a thread-guide and tensioning member forming a part of the present spool-winder.

Fig. 6 is an elevational view of my improved spool-winder showing it supported by a handle wholly independently of the surgical stitching instrument.

Referring more specifically to the drawing, the invention is illustrated in its preferred form as removably carried by a surgical stitching instrument comprising a supporting element 1, to one end of which is secured a curved eye-pointed needle 2. The opposite end of the support has secured thereto a handle 3 by means of which the instrument may be held and manipulated. The needle 2 is held within a needle-clamp 4 and is adapted to receive a suturing thread *t* carried by a spool *s* rotatably mounted in a spool-holder 5 supported by the instrument. The thread *t* passes from the spool *s* through a thread-guide 6, carried by the needle-clamp, thence along a groove (not shown) formed on the under side of the needle and finally through the needle-eye 7.

The needle-clamp 4 is actuated by means of an endwise movable rod 8 which passes lengthwise through the supporting element 1 and into the handle 3 where it is provided with a threaded

end 8a upon which is threaded a clamping nut 9. This nut comprises a cylindrical internally threaded portion 9a fitted within a bore 3a in the handle 3 and an enlarged portion 9b which engages the end of the handle and which has a knurled periphery by means of which the nut may be manually rotated to clamp and unclamp the needle. This needle and its clamping means are more fully shown and described in my co-pending patent application Serial No. 398,708, filed June 19, 1941.

As shown in Fig. 1 the nut 9 is provided with a longitudinal bore 9c into which projects the threaded end 8a of the needle-clamp actuating rod 8.

The improved spool-winding device comprises essentially two elements, viz, a thread-guiding and tensioning element A and a spool-holding and -rotating element B. The thread-guiding and tensioning element consists of a sleeve member 10 adapted to fit within the bore 9c and is internally threaded, at 10a, to engage the threaded end 8a of the rod 8. Projecting laterally from the sleeve 10 is an arm 11 having an offset end 11a provided with a thread-guiding eye 11b. Secured to the side of the arm 11, by screw 12, is the shank 13a of a spring thread-tensioning finger 13 which overlies the end 11a of member 11 and applies a slight tension to the thread *t* passed between the finger and the offset end 11a of the arm 11. At its rear side, the thread-tensioning finger 13 has a downturned portion 13b which overlies the edge of the portion 11a and retains the thread beneath the finger. The thread-guiding and tensioning element may be secured to the instrument by inserting the sleeve 10 into the bore 9c in the needle-clamping nut 9 and rotating the thread-guide to screw the sleeve onto the free end of the rod 8 until the shoulder 11c, on the element 11, abuts the head 9b of the nut 9.

The spool-holding and -rotating element B comprises a spindle 14 having at one end, a portion 14a adapted to have the spool to be wound placed thereon and then to be inserted into the sleeve member 10 to rotatably support the element B on the element A. The opposite end 14b, of the spindle comprises a finger-grip adapted to be engaged by the thumb and forefinger of a user whereby by relative movement between the thumb and finger the spindle may be manually rotated in the sleeve 10. The finger-grip is preferably of small diameter so that each normal movement between the thumb and finger will produce one rotation, or more, of the

spindle and the spool carried thereby. Preferably, but not necessarily, the finger-grip portion of the spindle is roughened or knurled to facilitate its rotation. Intermediate its ends, the spindle is formed with a circular flange 15, substantially equal in diameter to the diameter of the spool's to be wound, which carries a laterally projecting pin 16 adapted to enter any one of a plurality of holes 17 formed in the end flanges 18 of the spool, to effect rotation of the spool by rotation of the spindle.

As above described, the improved spool-winding device may be carried by the handle end of the surgical stitching instrument and therefore may be readily available for winding spools for use in the instrument. However, if desired, a separate handle may be provided for holding the device during the winding operation. Fig. 6 illustrates the winding device as supported by a handle H, of wood or other suitable material, having an axial bore 19 therein into which the sleeve member 10, hereinbefore mentioned, is frictionally or otherwise held.

To facilitate complete sterilization of the suture thread wound upon the spool, the hub portion h of the spool's is provided with a plurality of radial holes i which, in conjunction with the holes 17 in the flanges 18 of the spool, will enable the sterilizing medium to be brought into contact with all of the thread on the spool.

Operation

In operation, the sleeve 10 is inserted into either the handle 3 of the instrument, as shown in Fig. 1, and threaded onto the end of the needle-clamping rod 8, or into the handle H as shown in Fig. 6, the instrument or handle H being held in one hand of the user. The spool's is then slipped onto the reduced end portion 14a of the spindle and the pin 16 is inserted into one of the holes 17 in one of the flanges of the spool to lock the spool to the spindle. Next the reduced end portion 14a is inserted into the bore in the sleeve 10 and pushed inwardly until one flange of the spool contacts the slightly enlarged outer end 10b of the sleeve 10. Next, the end of the thread is passed through the thread-guiding eye 11b and the thread remote from the end is slipped under the tensioning finger 13 and behind the downturned portion 13b, as shown in Fig. 5. The end of the thread is then secured to the spool, for example, as by being passed through one of the holes 17 and temporarily held by the finger of the user. Rotation of the spindle by the other hand of the user then causes the thread to be wound on the spool which, after sterilization, may be placed in the spool-holder 5 of the instrument and threaded through the needle 2.

If desired, the spool-winder may be retained on the instrument during the suturing operation. However, if preferred, either the element B, or both the elements A and B, may readily be removed therefrom.

From the foregoing it will be perceived that this invention has provided a simple and inexpensive, manually supported and manually actuated winding device particularly adapted for winding spools designed to be used in surgical stitching instruments and that said device is designed to be supported either in the handle end of the instrument or in a separate handle provided for the purpose.

Having thus set forth the nature of the invention, what I claim herein is:

1. A manually supported and manually actu-

ated spool winding device comprising a hand-supported holder having a bore therein, a spool-holding spindle having at one end a spindle-rotating head and at its opposite end a cylindrical bearing portion removably journaled within the bore in said holder, means between said head and said bearing portion to lock said spindle to a spool to be wound, and means on said holder to guide a thread to said spool.

2. A hand-supported and hand-operated winding device for surgical suture spools comprising a hand-supported holder having a bore therein, a spool-holding spindle having at one end a cylindrical portion journaled within said bore and at its other end a knurled finger grip adapted to be held between the thumb and finger of a user and being of such size that one normal rolling movement thereof between the thumb and finger gives the spindle approximately one complete rotation, means between said cylindrical portion and said finger grip to support a spool to be wound and to key the spool to said spindle for rotation therewith, and means on said holder to guide a thread tangentially to said spool.

3. A manually supported and manually actuated winding device comprising a hand-supported holder having a bore, a manually rotatable spindle, a portion of which is adapted to receive a spool to be wound, a flange intermediate the ends of said spindle, a pin projecting from said flange and adapted to engage said spool to effect rotation of said spool with said spindle, said spindle having a portion at one side of said flange rotatably journaled in the bore in said holder and a roughened surface at the opposite side of said flange to facilitate manual rotation of the spindle.

4. A hand-operated winding device for surgical suture spools comprising a handle adapted to be held in one hand of a user, a sleeve secured in said handle, a manually rotatable spindle having one end rotatably journaled in said sleeve and a finger-grip adjacent the other end for effecting rotation of the spindle by the other hand of the user, means intermediate the ends of said spindle for locking a spool thereto for rotation by the spindle, and an arm projecting radially from said sleeve and provided with a thread-guiding eye in alignment with said spool.

5. A hand-operated winding device for surgical suture spools comprising a handle adapted to be held in one hand of a user, a sleeve secured in said handle, a manually rotatable spindle having one end rotatably journaled in said sleeve and a finger-grip adjacent the other end for effecting rotation of the spindle by the other hand of the user, means intermediate the ends of said spindle for locking a spool thereto for rotation by the spindle, an arm projecting radially from said sleeve and provided with a thread-guiding eye in alignment with said spool, and a yielding thread-tensioning device carried by said arm and engaging the thread adjacent said thread-guiding eye.

6. A hand-operated spool winding device designed to be removably attached to the handle of a surgical stitching instrument having a needle-clamp and clamp-actuating means including a screw and a cooperating nut having a longitudinal bore located within said handle, comprising a manually rotatable spindle having one end journaled coaxial with said bore and a finger-grip adjacent the other end for effecting rotation of the spindle by the thumb and finger of a user.

means intermediate the ends of the spindle for locking a spool thereto for rotation by said spindle, and an arm projecting laterally from the axis of said handle at one side of a spool held on said spindle and normally engaging said nut to hold the arm in operative position, said arm being provided with a laterally off-set portion having a thread guiding eye aligned with a spool on the spindle to direct thread to the spool.

7. A hand-operated winding device for surgical suture spools as set forth in claim 6 in which the off-set portion of the arm carries a thread tensioning device for applying a tension to the thread in its travel to the spool.

8. A spool winding device constructed and arranged to wind suturing thread on spools to be used in surgical stitching instruments, comprising a handle having a bore in one end thereof, a spindle having at one end a portion adapted to be grasped between the thumb and finger of a user by which the spindle is rotated and at its opposite end a portion rotatably supported in the bore in said handle, said spindle also having, intermediate its ends, a portion for supporting a spool to be wound and a flange against which said spool abuts, interengaging means provided by said flange and spool for locking the two together against relative rotation so that rotation

of the spindle also effects rotation of the spool, and an arm removably secured to said handle and projecting outwardly therefrom and having a thread-eye aligned with the spool on the spindle to direct the thread to the spool.

- 5 9. A spool winding device constructed and arranged to wind suturing thread on spools to be used in surgical stitching instruments, comprising a handle having a bore in one end thereof, 10 a spindle having at one end a portion adapted to be grasped between the thumb and finger of a user by which the spindle is rotated and at its other end a portion rotatably supported in the bore in said handle, said spindle also having, intermediate its ends, a portion for supporting a spool to be wound and a flange against which said spool abuts, interengaging means provided 15 by said flange and spool for locking the two together against relative rotation so that rotation of the spindle also effects rotation of the spool, 20 an arm removably secured to said handle and projecting outwardly therefrom and having a thread-eye aligned with the spool on the spindle to direct the thread to the spool, and a thread-tension device carried by said arm and engaging 25 the thread to apply a slight tension thereon in its passage to the spool.
